US00D676867S

(12) **United States Design Patent**
Walsh et al.

(10) Patent No.:

US D676,867 S

(45) Date of Patent: ** Feb. 26, 2013

- (54) **THEMATIC USER INTERFACE FOR A PORTION OF A DISPLAY SCREEN**

(75) Inventors: **Daniel Walsh**, San Francisco, CA (US);
Jacob Surber, San Mateo, CA (US)

(73) Assignee: **Adobe Systems Incorporated**, San Jose, CA (US)

(**) Term: **14 Years**

(21) Appl. No.: **29/378,238**

(22) Filed: **Nov. 1, 2010**

(51) **LOC (9) Cl. 14-04**

(52) **U.S. Cl. D14/488; D14/486**

(58) **Field of Classification Search D14/485-495;**
D18/24-33; D20/6, 52; D21/324-333;
715/700-867, 973-977

See application file for complete search history.
